ELECTRIC GASEOUS DISCHARGE DEVICE

Jean Lecorguillier, Suresnes, France, assignor to
General Electric Company, a corporation of
New York

Application February 2, 1939, Serial No. 254,148
In Switzerland February 2, 1938

2 Claims. (Cl. 176—126)

- The present invention relates to electric gaseous discharge devices, and especially to devices of the self-rectifying type which employ a plurality of anodes.
- 5 It is known to use gas discharge tubes on a single or multi-phase supply, the tube operating as self-rectifier and being provided for this purpose at one end with two or more anodes and at the opposite end with a cathode of any desired type. In these tubes, usually known as "Cooper-Hewitt" tubes, the anodes are arranged in straight or bent arms of a length depending on the voltage which must exist between the anodes in order to avoid short-circuits between them. Such a construction is bulky and fragile especially when applied to tubes used for lighting and moreover, the initial cost is high, as the tube can hardly be produced except by hand.
- The present invention has for its chief object 20 the provision of an assembly of small bulk and great strength having excellent electrical stability and easily lending itself to mechanical production by reason of the fact that the anodes of the discharge tube are attached to one and the same foot tube in the interior of the discharge tube. However, this method of mounting the anodes, where, in the case of Cooper-Hewitt tubes, the working conditions justify the use of anode arms, is suitable only if in the tube under consideration 25 it does not cause a reverse current, which might result in a considerable volatilization of the anodes and a strong absorption of the gaseous filling, or in short-circuits between the anodes.
- According to the invention this result is obtained by so arranging the anodes that the anode parts which extend along the wall of the tube are for at least a portion of their length, measured from their front ends facing the discharge, located at a distance from the said wall sufficiently small to allow the anodes to be affected 35 by the discharge substantially only in the vicinity of their front ends and that the parts of the anodes which are adjacent one another are separated by a distance which is at least equal to the minimum spacing which is practically attainable without risk of contact between the anodes, but is less than the distance at which a harmful reverse current is produced, the current leads to the anodes being so arranged as to avoid 40 any discharge between the said leads. The two distances in question depend upon the particular conditions under which the tube is to operate, viz. the nature and spacing of the electrodes, the nature and pressure of the gaseous filling and the magnitude of the rectified current and of the 45 inter-anode voltage. The distance here considered between the anode parts and the wall is sufficiently small to prevent the ionization of the space situated at the rear of the front ends of the anodes; the distance between the two anodes 50 is of the order of magnitude of a few mean free paths of the electrons in the gaseous filling of the tube.
- Thanks to this arrangement the desired effect is easily obtained by suitably selecting the working conditions of the tube. It suffices, for example, when considering the minimum spacing between anodes, which is the optimum condition for the purpose desired, to take the inter-anode voltage as a variable and to determine by known means the other data, so that the reverse current 55 is sufficiently small to prevent any appreciable absorption of the gaseous atmosphere and that its point along the curve which gives the effective inter-anode voltage as a function of the reverse current is located on the straight portion of the said curve.
- The invention relates more especially to tubes having a positive luminous column and filled with rare gas or metallic vapor (with or without an auxiliary rare gas). It is however also capable of other applications, notably for the construction of tubes intended for rectifying alternating current, particularly in the case of low output 60 tubes.
- The invention will be more clearly understood from the following description taken in conjunction with the accompanying drawing which shows a number of examples. In the drawing:
- Fig. 1 is an elevational view of a self-rectifying single-phase lamp having anodes of the novel structure herein disclosed at one end thereof, 65
- Fig. 2 is a sectional elevation of the anode end of this lamp,
- Fig. 3 is a transverse section of the same lamp, 70 taken on the line 3—3 of Fig. 2,
- Fig. 4 is a sectional elevation of a modification of the lamp of Figs. 1—3, and
- Fig. 5 is a graph showing the relation of the voltage impressed between the anodes to the current flow therebetween.
- In this drawing, with particular reference to Figs. 1 to 3, the anodes 3, which are preferably of graphite, are of semi-cylindrical shape and are located at a distance *a* from the glass wall of the tube 7 which distance is sufficiently small to prevent the ionization of the intermediate space. The distance *b* between the two half-cylinders is also very small, of the order of a few mean free paths of the electrons in the gaseous atmosphere 75 of the tube. Further, in order to prevent a discharge from occurring between the current lead-in wires 5 and the anodes 3, these wires are each encased in a glass cap 6, each of which extends slightly into the corresponding anode and is fixed 80 to the anode at 4. Experience has shown that the paths of the discharge between anodes, such as *s* which are the only ones which are of substantial length, constitute no serious danger of faulty operation. The assembly is mounted on 85

the foot tube 11. At the other end of the tube 7 there is located a cathode 1 of any suitable construction, preferably of the activated thermionic type.

5 In the modification shown in Fig. 4 the two anodes 12 and 13 are concentrically arranged the one within the other, the radial distance d between them being of the order of a few mean free paths. The anode 12 is provided with a 10 flange and it is the plane surface of this flange, facing the positive column of the discharge which, almost alone, is affected by the discharge. The radial space c between the flange and the wall of the tube being small, the existence of discharge 15 paths such as t which pass around the anode 12 is avoided as is also the ionization of the space at the rear of the said flange.

The end of the anode 12 opposite the front end has an inwardly directed portion 16 which is 20 screwed to a threaded piece 17 electrically connected to the current lead-in wire 19, while the anode 13 is screwed to a threaded part 14 which in turn is connected to the lead-in wire 15. A tube 18 made of refractory material surmounts 25 the cap 20 on the stem-press and extends slightly into a recess provided in the anode 13. The object of this tube is to fix the spacing between the upper plane surface of the portion 16 of the anode 12 and the adjacent extremity of the inner anode 13 so as to give it a value of the same order of magnitude as d , and to prevent any discharge 30 between the two lead-in wires. As a further precautionary measure this refractory tube is preferably cemented to the cap 20 by means of a 35 suitable cement. The assembly is mounted on the foot tube 21.

Figure 5 shows the curve C giving the effective voltage v between the anodes as a function of the reverse current i for a given tube. It will 40 be seen that the said curve comprises a straight portion along which must be taken the point P corresponding to operation which does not give rise to a harmful reverse current. If a value of the main rectified current is desired above that 45 for which the curve C has been determined, another curve, such as for example C¹ is obtained based upon this different current. This curve likewise has a straight portion along which another operating point can be chosen for the tube 50 being tested without changing the remaining working conditions.

By way of a practical example the following are the dimensions of a preferred embodiment of a mercury vapor tube having an auxiliary filling 55 of rare gases and constructed as shown in Fig. 4:

Internal diameter of tube	mm.	32
Length of tube	metre	1
Rectified current emitted by the cathode	amps.	2.5 to 3
External diameter of flange of the external anode	mm.	30
Diameter of internal anode	mm.	13
Space between anodes	mm.	2.5
Using argon as auxiliary filling gas at a pressure of 0.4 mm. of mercury such a device can withstand an effective voltage of 400 between anodes, the reverse current being 0.1 ma. only. At a pressure of 0.8 mm. of mercury, the inter-		
70 anode voltage may reach about 370 volts.		

While the invention has been described by reference to certain specific embodiments thereof,

it is to be understood that the invention is not confined thereto, and that various changes, omissions and substitutions, within the scope of the appended claims, may be made therein without departing from the spirit thereof.

What I claim as new and desire to secure by Letters Patent of the United States, is:

1. An electric discharge tube containing a gaseous atmosphere and having a cathode at one end and at least two anodes mounted adjacent each other in the interior of the discharge tube at the other end thereof, said anodes being mounted coaxially and one within the other, the smaller anode having an outer cylindrical surface and the larger anode having cylindrical inner and outer surfaces the outer cylindrical surface of the larger anode extending along the wall of the tube being for at least a portion of its length, measured from the front end of said anode facing the discharge, located at a distance 20 from the said wall which is less than several times the mean free electron path in said atmosphere to allow the said larger anode to be affected by the discharge substantially only in the vicinity of its front extremity, and wherein 25 the cylindrical surfaces of the anodes which are adjacent one another are separated by a distance which is at least equal to the minimum spacing which is practically attainable without risk of contact between anodes but is less than a distance of several mean free electron paths in said atmosphere at which a harmful reverse current is produced, the current lead-in wires to the anodes being shielded to avoid any discharge between the said wires.

2. An electric discharge tube containing a gaseous atmosphere and having a cathode at one end and at least two anodes mounted adjacent each other in the interior of the discharge tube at the other end thereof, said anodes being mounted 40 coaxially and one within the other, the smaller anode having an outer cylindrical surface and the larger anode having cylindrical inner and outer surfaces, the outer cylindrical surface of the larger anode extending along the wall of the 45 tube being for at least a portion of its length, measured from the front end of said anode facing the discharge, located at a distance from the said wall which is less than several times the mean free electron path in said atmosphere to 50 allow the said larger anode to be affected by the discharge substantially only in the vicinity of its front extremity, and wherein the cylindrical surfaces of the anodes which are adjacent one another are separated by a distance which is at least 55 equal to the minimum spacing which is practically attainable without risk of contact between anodes but is less than a distance of several mean free electron paths in said atmosphere at which a harmful reverse current is produced, said outer anode being provided with a flange at its front end and a radially inwardly directed portion at its other end, the plane upper surface of the said inwardly directed portion being spaced 60 from the adjacent end of the inner anode by distance of the same order of magnitude as that which separates the said cylindrical surfaces of said anodes, the current lead-in wires of the anodes being shielded to avoid any discharge 65 between the said wires.
